DISPENSING CONTAINER FOR POWDERED HOUSEHOLD PRODUCTS

Alfred D. Sterges, Los Angeles, and Louis K. Warden,
Balboa, Calif., assignors to Purex Corporation, Ltd.,
South Gate, Calif., a corporation of California

Filed May 2, 1960, Ser. No. 60,404

Term of patent 14 years

(Cl. D58—17)

FIG. 2.

FIG. 1.

FIG. 3.

FIG. 4.

FIG. 5.

FIG. 1 is a side elevational view of a dispensing container for powdered household products showing our new design;

FIG. 2 is a top plan view of FIG. 1, in which the broken lines are for illustrative purposes only;

FIG. 3 is a bottom plan view of FIG. 1; and

FIGS. 4 and 5 are fragmentary sections taken respectively on lines 4—4 and 5—5 of FIGS. 2 and 3.

The side not shown is the same as the side shown.

We claim:

The ornamental design for a dispensing container for powdered household products, substantially as shown and described.
